APPARATUS FOR PLUNGER LIFT
CONTROL

Harold W. Fletcher, Houston, Tex., assignor to
Hughes Tool Company, Houston, Tex., a cor-
poration of Texas

Application September 29, 1934, Serial No. 746,063

5 Claims. (Cl. 103—52)

My invention relates to the control of the plunger in plunger lift pumps.

In devices of this character, the liquid is raised from the bottom of the well by pneumatic pressure exerted below the plunger to lift said plunger and a load of liquid from the well and discharge said load at the upper end of the eduction tube. After the load of liquid passes from the tube, the charge of air or gas behind the plunger also 5 discharges from the eduction tube and the plunger drops back in the tube to the lower end thereof to engage another load of liquid and repeat its cycle. However, the plunger tends to fall in the eduction tube before the charge of 10 air or gas which was employed to raise the plunger has had time to exhaust. The result is that the plunger may be caught in the rising flow of gaseous pressure fluid and be blown back up to the top. The valve in the plunger which was 15 opened after the load was discharged may sometimes be closed and the falling of the plunger through the gas and liquid in the tube may be greatly interfered with and the operation of the device rendered ineffective. This is especially a 20 serious problem when the well is a small producer and the load discharged at each stroke of the plunger is small.

It is an object of this invention to regulate the discharge of fluid from the well in such a manner that the falling of the plunger will not be 25 impeded.

I desire to delay the exhaust of the gaseous pressure fluid until the plunger has had time to fall sufficiently to avoid being caught by the blast 30 of pressure fluid.

The invention contemplates the use of an air or gas relief valve, operating to release the pressure fluid when a predetermined pressure in the well is attained. The lowering of pressure is 35 delayed by the charge of liquid lifted by the plunger.

In the drawing herewith, Fig. 1 is a side view showing the assembly of apparatus employed in my invention, the well casing and tube being in 40 central vertical section.

Fig. 2 is a vertical section showing the lower 45 end of the well equipment.

Fig. 3 is a longitudinal section of my pressure relief valve.

50 The plunger lift device to which my invention is applied is now in common use. The well is equipped with a casing 1, extending down to the producing stratum. It has a casing head 2 formed with a lateral fluid outlet 9. Above the 55 head is a cap or nipple 4 closing the upper end

of the casing head and connecting to the eduction tube extension 5.

The eduction tube 6 has a fluid tight support at 7 in the casing head. It is perforated at 8 in the casing head to allow discharge of fluid from the eduction tube to the flow line 9. The lower end of the eduction tube, shown in Fig. 2, is provided with a perforated intake plug 10 connected to the tube by a coupling 11. Within said coupling is a cross shaped stop member 12 10 which is adapted to be engaged by the valve stem 13 on the valve 14 in the plunger 15. Said plunger is shown at the lower end of its stroke with the valve in closed position at the lower end of the passage through the plunger. 15

At the upper end of the eduction tube extension 5 is a cap 16 which closes the tube and also houses a shock absorbing sleeve 17 of rubber or similar resilient material. There may be a by-pass 18 from the upper end of this cap to the 20 flow line 9 equipped with a valve 19, to allow the escape of fluid from the tube extension when the plunger is to be allowed to enter the said extension.

To control the discharge of liquid and gas or 25 air, I employ a container 20 in the flow line 9. At the lower end of said container is a liquid outlet 21 having a choke valve 22 therein. At the upper end of container 20 is a gas outlet 23 which connects into the flow line beyond the valve 22. 30

In the gas conducting pipe 23 is an automatically operating valve, working within the casing 24. This valve is shown best in Fig. 3. The passage 25 through casing 24 is controlled by a balanced valve 26 mounted upon a stem 27 working through the upper wall of said casing. The upper end of said stem is secured to a flexible diaphragm 28 within a casing 29. Said diaphragm divides the casing 29 into a lower closed chamber 30 and an upper chamber 31 which has 40 connection by means of pipe 32 to the upper end of the casing head at 33. The valve is acted upon by a weight or spring acting to normally move the valve to open position. I have shown a weight 37 mounted upon a lever arm 34, pivoted at 35 to the support 38 and connected to the valve stem 27 at 36. The effectiveness of the weight may be varied by moving it along the lever arm, as will be obvious. 45

In the operation of the pump, if gas from the 50 well is sufficient to raise the load, no artificial pressure will be required, but ordinarily gas under pressure will have to be forced into the well through a lateral pipe 3 connected with the casing head below the seal formed at 7. This gas 55

will exert pressure upon the liquid in the well and depress the level in the casing and raise it in the tube until the gas can enter the perforations at 10 and bubble up below the plunger and there accumulate until the pressure is sufficient to raise the plunger and its load to the surface.

The liquid will discharge into container 20 where its outflow will be regulated by the choke valve 22. The outlet for the gas will be closed 10 by the pressure of fluid exerted through the pipe 32 to the upper end of the valve rod 27. Gas cannot escape, therefore, until the liquid has passed from the container 20. I arrange the weight 37 on the valve to open the valve at a predetermined pressure against the upper side 15 of the diaphragm 28.

When the liquid is discharged from the eduction tube the plunger will pass into the closed upper end of the eduction tube where it will be stopped by the back pressure of gas and liquid in the tube above it. The valve in the plunger will be forced open and the plunger will then fall. As the gas in the tube cannot exhaust at 20 once, the plunger will not be impeded in its fall until it has reached the desired level below the 25 top of the tube.

When the liquid has discharged from the container, the gas will immediately tend to also escape through valve 22 and the gas pressure will soon be lowered in amount so that the air valve 26 will also open and allow full and rapid exit of the pressure fluid from the well. The device is timed by the setting of the liquid outlet valve 22 and the control valve 26 so that the plunger is allowed to fall as far as is necessary to avoid the flow of gas or air which occurs at the upper end of the tube when the outlet therefor is opened. Thus if the working pressure is 100 pounds per square inch, it might be found correct 40 to set the valve 26 to open when the well pressure drops to 75 pounds. When this point is reached the plunger will have dropped sufficiently and the control valve may open to allow full and rapid exhaust of gaseous fluid pressure in the eduction and permit the entrance of liquid to the lower end of the tube before the plunger arrives 45 at the bottom.

The use of the control valve 26 effects a better control of the gas discharge than would be possible by the use of the choke valve 22 above. For, if the valve 22 is choked down enough to properly time the discharge of liquid from the container, it will also interfere with the rapid discharge of the gas. By allowing the gas to bypass 55 rapidly at the proper time, the plunger is more efficiently operated and liability to the blowing of the plunger back is eliminated.

What I claim as new is:

1. A plunger lift device including a well casing, 60 an eduction tube therein, a pneumatically operated plunger movable freely from end to end of said tube, a container positioned to receive the liquid raised by said plunger, a discharge outlet from said tube to said container, a flow line connected with the lower end of said container,

a choke valve in said line to control the rate of emptying of said container, a gas bypass from the upper end of said container to said flow line downstream from said valve, and a control valve in said bypass adapted to open when the fluid pressure in said discharge outlet reaches a predetermined minimum amount. 5

2. A plunger lift device including a well casing, an eduction tube therein, a pneumatically operated plunger movable freely from end to end of said tube, a container positioned to receive the liquid raised by said plunger, a discharge outlet from said tube to said container, a flow line connected with the lower end of said container, a choke valve in said line to control the rate of emptying of said container, a gas bypass from the upper end of said container to said flow line downstream from said valve, and means to bypass gas from said container past said choke valve responsive to a predetermined minimum fluid pressure in said discharge outlet. 15

3. A plunger lift device including a well casing, an eduction tube therein, a pneumatically operated plunger movable from end to end of said tube, and an outlet line from said tube for fluid raised by said plunger; in combination with a container connected with said outlet to receive the full load of liquid raised by said plunger, means to control the rate of flow of liquid from said container, an exit for gas from said container, a valve controlling said exit, and a control device on said valve acting in response to the operating fluid pressure in the well to close said valve when the liquid is discharged to said container and to again open said valve in response to a drop of fluid pressure in said outlet line to a predetermined minimum. 30

4. A plunger lift device including a well casing, an eduction tube therein, a pneumatically operated plunger movable from end to end of said tube, and an outlet line from said tube for fluid raised by said plunger; in combination with a container connected with said outlet to receive the full load of liquid raised by said plunger, means to control the rate of flow of liquid from said container, and separate means to control the escape of gas from said container operating in response to a predetermined fluid pressure in said outlet line after said liquid has emptied from said container. 60

5. A plunger lift device including a well casing, an eduction tube therein, a pneumatically operated plunger movable from end to end of said tube, and an outlet line from said tube for fluid raised by said plunger; in combination with a container connected with said outlet to receive the full load of liquid raised by said plunger, means to control the rate of flow of liquid from said container, and separate means controlled by the fluid pressure in said outlet line to allow escape of gas from said container after said plunger has dropped in said tube a desired distance. 65
